The ornamental design for a container base, as shown and described.

DESCRIPTION

FIG. 1 is a top, front perspective view of a container base showing my new design;

FIG. 2 is a bottom, rear perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines shown in the drawings represent portions of the container base and form no part of the claimed design.
